FIG. 1.

FIG. 3.

FIG. 2.

Inventor
WILLIAM G. PARMELE.

By *O. Haughey, Jr.* Attorney

UNITED STATES PATENT OFFICE.

WILLIAM G. PARMELE, OF SEATTLE, WASHINGTON.

LIFE-SAVING DEVICE.

1,400,976.

Specification of Letters Patent. Patented Dec. 20, 1921.

Application filed January 11, 1921. Serial No. 436,519.

To all whom it may concern:

Be it known that I, WILLIAM G. PARMELE, a citizen of the United States, residing at Seattle, in the county of King and State of Washington, have invented certain new and useful Improvements in Life-Saving Devices; and I do hereby declare the following to be a full, clear, and exact description of the invention, such as will enable others skilled in the art to which it appertains to make and use the same.

This invention relates to a life saving device, and more particularly to a device known as a swimmer's collar, or buoyant collar.

The object of the invention is to provide a buoyant device, preferably consisting of an inflated rubber tube, of circular form, to be slipped over the head of the user, and allowed to encircle the neck.

A further object is to provide a device of the character indicated which will require no fastening device, the article being of the required size and being sufficiently elastic to permit of passing over the head of the user, without danger of accidental displacement.

A still further object is to provide a device which when in position will not interfere with swimming or plunge diving.

With the foregoing and other objects in view, the invention consists in the provision of an air inflated, or other buoyant member, proportioned to fit the neck of the user, and being slightly elastic, and having sufficient displacement to prevent the individual using the article from sinking beyond his depth.

In the accompanying drawings:

Figure 1 is a perspective view of the device, in position for use.

Fig. 2 is a fragmentary view, chiefly in section, showing especially the connection by means of which the device is inflated.

Fig. 3 is a plan view of another form.

In carrying out my invention, I provide a buoyant member 10, shown in the first instance as consisting of a rubber tube, of suitable proportions and adapted to be inflated with air through the connection 12, which is closed by the valve 14.

Although a valve connection has been shown, permitting of inflation and deflation as desired, it is entirely practicable to inflate the tubular member, and seal the con-

nexion in such manner that the device may be used for an extended period without the necessity of again filling it with air.

One of the chief objections to safety device of the type or types in common use is that they interfere more or less with the movements of the user in bathing and in learning to swim. In making use of this collar, the difficulty referred to is largely or wholly eliminated, and especially is this true when plunge diving is indulged in. As previously intimated, the tube is sufficiently elastic when inflated to permit of the user passing the article over his head, but subsequent displacement by accident is prevented, owing to the contraction of the rubber.

While reference has been made to the use of an expansible member to be inflated with air, it is obvious that an expansible collar of any construction, formed of buoyant material, will serve the purpose. For instance, I have shown in Fig. 3 a device of this type formed of a plurality of segmental sections 10' connected by elements 15, at least one of which is elastic. In this form the buoyant elements may be of rubber, or if not so made, the elastic connecting portion or portions will permit of the expansion of the device, so that it may be slipped over the head, and will then fit snugly without causing inconvenience. All surfaces of the elements 10' are preferably rounded, as shown. These portions may be of standard size, and variation in size of the complete device may be secured by using elements 15 of the required length, or by reducing the length of any one of them, when the parts are first assembled, or subsequently.

Having thus described the invention, what I claim is:

A life saving apparatus consisting of a continuous buoyant body passable over the head of the wearer and contractile about the neck to assume a position intermediate the head and shoulders, and said body having a reduced elastic portion to facilitate contraction and expansion.

In testimony whereof I affix my signature in presence of two witnesses.

WILLIAM G. PARMELE.
